By his Attorney Carl P. Goepel

UNITED STATES PATENT OFFICE.

GERHARDT F. SCHWARTZ, OF ST. LOUIS, MISSOURI.

THERMOSTATIC VALVE.

1,324,070.

Specification of Letters Patent.

Patented Dec. 9, 1919.

Application filed August 26, 1918. Serial No. 251,567.

To all whom it may concern:

Be it known that I, GERHARDT F. SCHWARTZ, a citizen of the United States, and a resident of St. Louis, Missouri, have 5 invented certain new and useful Improvements in Thermostatic Valves, of which the following is a specification.

The present invention relates to improvements in thermostatic valves, and particularly such a valve having a snap action, the opening and closing action being instantaneous when the heated medium has reached either of the predetermined extreme 10 temperatures between which it is desired to maintain the said medium. An object of the invention is to provide such a valve which may be readily and accurately regulated from the outside of the casing without jamming the fulcrum points, or forcing the 15 lever out of proper alinement, or forcing the adjustment screw out of vertical alinement so that the threads on it jam against the casing, and which will despite such flexibility of movement be positive and forceful in action. It is also proposed in the present invention to prevent the gas from back firing and burning in the mixer, which often results from the gradual increasing of the 20 flow, and to this end I provide a snap acting 25 valve actuated by a cam or trip.

Another object is to provide such a valve having a maximum degree of movement with binding or frictional retardation reduced to a negligible quantity. With the 30 present invention it is proposed to permit the passage of gas, steam, water, vapor, or the like through the valve casing in such manner as to produce a device of this character of great compactness, and of simple 35 and inexpensive construction.

With these and other objects in view my invention is shown in the accompanying drawings, and will be hereinafter more fully described with reference thereto, and finally 40 pointed out in the claims.

In the accompanying drawings:

Figure 1 is a vertical sectional view of my improved valve,

Fig. 2 is a horizontal sectional view taken 50 along the line 2-2 of Fig. 1,

Fig. 3 is a vertical sectional view on the line 3-3 of Fig. 1,

Fig. 4 is a detail side view of the valve closure member, and

Fig. 5 is a top view thereof.

Similar reference characters indicate corresponding parts throughout the several figures of the drawings.

Referring to the drawings, and more particularly to Fig. 1 thereof, my invention 60 comprises a casing 10, having a threaded extension 11 at one end thereof, to which is secured one end of a bushing 12, which is screwed at its other end into the wall of the boiler, or heater 13, containing the heated 65 medium intended to be regulated by the valve. An elongated tube 14, preferably of copper or other suitable material having a high degree of expansion and contraction by heat or cold is secured to the inner wall of 70 the bushing 13 and extends into the boiler, being closed at its end by a plug 15, and interiorly is provided with a porcelain rod 16, the ends of which respectively engage the said plug 15, and a steel rod or plunger 17 75 disposed within a passage 18 provided in the extension 11 of the casing.

Within the casing at the rear of the passage 18, there is provided a supporting lug or projection 19, to either side of which are 80 pivoted the legs 20, 21 of a hinged block 22, extending forwardly in the casing and provided at each side with upwardly extending pillars or projections 23 and 24.

A set screw 25 provided in the casing engages the lower side of the block 22, and is provided at its outer end with a knurled head.

Between the lower end of the plunger 17 and the upper surface of the block 22, there 90 is disposed the short end of a lever 26, the knife edges of the fulcrum extensions 27 and 28 thereof resting respectively on the projections 23 and 24, and a knife edge 29 on the upper side of the lever engaging the lower 95 end of the said plunger. The lever is thus enabled to function properly in any position of adjustment without jamming on the block 22 or the plunger 17. The long arm of the lever is stepped in shape and extends to the 100 forward end of the casing, a spring 30 being arranged intermediately between the lever and the upper side of the casing.

At its forward end the lever is connected to a trip lever 31 fulcrumed at 32 to a depending support 33, by means of a pitman or connecting link 34 pivotally connected at its ends respectively to the lever 31 and a projection 34^a on the lever 26. A triangular cam 35 is provided on the end of the lever 110

31, which engages a small roller 36 provided on the end of a lever 37, fulcrumed at 38 to a depending support 39 pivotally secured to a lug 40 on the upper wall of the casing. The 5 roller 36 is held in engagement with the cam 35 by means of a spring 41, connecting the said cam and the support 39, a similar spring (not shown) being provided at the other side.

10 Gas, steam, oil, water, vapor, or other medium enters the thermostatic case by means of a pipe 42, and leaves by a pipe 43, in which is disposed a sliding valve closure 44, having an upwardly extending guide portion 45 having preferably four quarter angles, which permit the flow of gas, and at the same time guide the valve vertically, and a downwardly extending portion 46 provided with a rectangular opening 47 therein 15 in which is disposed the end of the lever 37.

The operation of my improved device is as follows: Assuming the valve to be in the closed position shown in Fig. 1, the supply of gas being cut off. The heating medium 20 within the boiler gradually cools causing a corresponding contraction of the copper tube 14. It will be seen that as the tube 14 contracts, the porcelain rod within will be forced downwardly together with the plunger, causing pressure on the short arm of the 25 lever 26, which lifts the long arm. As the long arm is lifted the triangular cam on the end of the lever 31 is forced downwardly, the inclined surface moving the lever 37 30 longitudinally. The jointed connection between the levers 31 and 26 prevents any appreciable binding or friction during the action of the valve. This action continues until the point of the cam comes in line with 35 the axis of the roller, whereupon with a snap movement the roller slides along the upper inclined surface of the cam, depressing the outer end of the lever 37 and drawing the closure member 44 into open position. Gas thereupon enters the pipe 43, escaping from the casing through the four 40 quarter angles of the portion 45 of the valve. As the heating medium again becomes heated, the copper tube expands, and the 45 valves operate to close in a reverse manner, the spring 30 holding the knife edge 29 in engagement with the plunger, and forcing the lever 26 gradually downward correspondingly with the expansion of the 50 tube 14.

In order to regulate the valve the short arm of the lever is raised or lowered, as the case may be, by turning the set screw 25 from the outside of the casing. In this manner the valve may be accurately adjusted, 60 without jamming of the fulcrum points, effecting the alinement of the parts, or forcing the adjustment screw out of vertical alinement so that the threads on it jam 65 against the casing. The action of the trip

lever is without binding or frictional retardation.

By reason of the snap acting valve, back fire is effectually prevented.

I have illustrated and described a preferred and satisfactory form of my invention, but it is obvious that changes may be made therein within the spirit and scope thereof, as defined in the appended claims.

I claim:

1. In a thermostatic valve, an expandible and contractible element, a lever adapted to be moved thereby, a hinged member adapted to support the fulcrum point of said lever, means for raising and lowering said hinged member, said fulcrum point having longitudinal sliding engagement with said hinged member whereby movement of said member about its hinge effects raising and lowering of said lever but does not move the same longitudinally, a valve, and means operated by said lever adapted to open and close said valve.

2. In a thermostatic valve, an expandible and contractible element, a lever adapted to be moved thereby, a hinged member adapted to support the fulcrum point of said lever at one side, an adjustable set screw engaging said lever at the other side substantially in line with said fulcrum point, said fulcrum point having sliding engagement with said hinged member whereby movement of said member about its hinge effects raising and lowering of said lever but does not move the same longitudinally, a valve, and means operated by said lever adapted to open and close said valve.

3. In a thermostatic valve, an expandible and contractible element, a lever adapted to be moved thereby and having a knife edged fulcrum, a hinged member adapted to support the fulcrum point of said lever, means for raising and lowering said hinged member, said fulcrum point having longitudinal sliding engagement with said hinged member whereby movement of said member about its hinge effects raising and lowering of said lever but does not move the same longitudinally, a valve, and means operated by said lever adapted to open and close said valve.

4. In a thermostatic valve of the character described, an expandible and contractible element, a lever of the first class engaged at its short arm by said element and adapted to be moved thereby, a hinged member having swinging movement transversely of the length of said lever and adapted to support the fulcrum point of said lever, adjustable means for swinging said hinged member, said fulcrum point having longitudinal sliding engagement with said hinged member whereby movement of said member about its hinge effects raising and lowering but does not move the same longi-

tudinally, a valve, and means operated by said lever adapted to open and close said valve.

5. In a thermostatic valve, an expansible and contractible element, a lever adapted to be slowly moved thereby during expansion and contraction, means adapted to support the fulcrum point of said lever, a valve, a pivoted member adapted to open and close 10 said valve and a lever having point contact with the end of said pivoted member, means yieldably holding said lever in engagement with said pivoted member, said last mentioned lever adapted to be actuated by means 15 of said first mentioned lever and adapted to fully actuate said pivoted member as said last mentioned lever moves at either side of the dead center formed by said point contact, said pivoted member being stationary 20 during movement of said last mentioned member at the other side of the dead center.
6. In a thermostatic valve of the character described, an expansible and contractible element, a lever adapted to be slowly moved 25 thereby during expansion and contraction, means adapted to support the fulcrum point of said lever, a valve, a pair of levers disposed end to end, a pivoted support pivotally supporting one of said levers intermediate 30 its ends and permitting longitudinal and swinging movement thereof, a support pivotally supporting the other of said levers, one of said levers having a pointed end, a roller at the end of the other of said levers 35 engaged by said pointed end, means yieldably holding said levers in engagement, one

of said levers being connected to said valve, the other of said levers being connected to said first mentioned lever and adapted to be actuated thereby, said lever connected to 40 said valve adapted to be fully actuated to open or close said valve as said roller is moved at either side of the dead center formed by said pointed end contacting therewith. 45

7. In a thermostatic valve, an expansible and contractible element, a lever adapted to be slowly moved thereby during expansion and contraction, means adapted to support the fulcrum point of said lever, a valve, 50 a pivoted member adapted to open and close said valve, and a lever having point contact with the end of said pivoted member, means yieldably holding said lever in engagement with said pivoted member, a jointed connection 55 connecting said last mentioned lever to said first mentioned lever, said last mentioned lever adapted to be actuated by means of said first mentioned lever and adapted to fully actuate said pivoted member as said last mentioned lever moves at either side of the dead center formed by said point contact, said pivoted member being stationary during movement of said last mentioned member at the other side of the dead center. 65

In testimony that I claim the foregoing as my invention, I have signed my name.

GERHARDT F. SCHWARTZ.
